CLASSIFIER FOR MATERIAL REDUCTION MILLS

David Weston, Toronto, Ontario, Canada

Application August 14, 1951, Serial No. 241,807

Claims priority, application Canada August 1, 1951

14 Claims. (Cl. 209—26)

The present invention relates to an apparatus for recovering from an air stream entrained solid particles having a predetermined size-weight factor, and more particularly it relates to a classifier for use in connection with material reduction mills from which product is withdrawn in a stream of air whereby the separation and recovery of particles of particular size-weight factors from the air stream may be accomplished.

In the art of comminuting solid materials such as rock, ore and the like, it has long been recognized that basically it is desirable to produce a subdivided product in which the valuable constituents are present as essentially primary crystals, since the reduction in size of the individual particles to a further degree normally does not result in any benefit insofar as subsequent recovery of the values is concerned, but may on the other hand result in the formation of slimes, rendering subsequent recovery more difficult. On the other hand, if the material is not reduced to the point where the values are in the form of primary crystals, the particles themselves will be combined aggregates of gangue materials and values which cannot be separated from each other by normal mechanical means such as gravity concentration. In many reduction operations advantage may be taken of the fact that the basic size of the crystals of gangue materials differs from the basic crystal size of the values, and accordingly it has been found possible in many cases to reduce all of the material substantially to its primary crystalline state and then by making a separation of the product on the basis of particle size, to separate the product into a concentrate rich in values and a tailing containing most of the gangue materials.

There are in addition a number of instances where values occur in relatively large bundles of primary crystals and where it is desirable insofar as possible to separate these bundles from the gangue without breaking them up. One such case, for instance, is asbestos, which normally occurs as densely packed bundles of substantially pure asbestos fibres in a host rock having a relatively fine primary crystal structure. In recovering asbestos fibre, the relative value of the pure asbestos recovered primarily varies with the length of the fibres, the relative value of the fibres of $\frac{1}{2}$ inch length and over being many times the relative value of fibres, say of under $\frac{1}{8}$ inch in length. As is well known, however, primary asbestos fibres are comparatively delicate and any overgrinding of them will reduce their length and consequently their relative value per unit weight. Moreover, since primary crystals of asbestos have the form of exceedingly slender filaments and the air resistance of each individual filament is great, having regard to the weight of the filament, separation of primary fibre from granular fines in the usual air separators, cyclones and the like, is very difficult, the result being that in order not to lose a substantial quantity of product the asbestos is normally collected as a relatively impure mixture of the granular and fibrous material, which then has to undergo a complicated cleaning process during which the granular material is eliminated. There has, accordingly, long been a recognized need in the art for a means of separating and recovering bundles of asbestos fibre as soon as they are set free during a reduction operation and before the individual bundles have been broken down into primary fibres.

Similarly, in the comminution of various other ores where relatively large particles of values occur, it may

2

be advantageous to recover these large particles as they are freed, and to form a coarse concentrate from them.

The present invention is adapted for use in connection with material reduction mills of the type wherein the product is removed from the mill in a stream of air and has as its principal object the provision of a classifier arranged to form a part of the air circuit in a mill of this type which is capable of removing from the air stream all particles having a size-weight factor above a predetermined value, and recovering therefrom such particles as are within a given size range.

It is also an object of this invention to provide such a classifier which is essentially simple in construction and requires a minimum of maintenance during operation.

It is a further object of the invention to provide such a classifier which may be arranged in series with other such classifiers to provide a series of products within different predetermined size ranges.

Other objects and advantages of the invention will be apparent as the specification proceeds.

A classifier according to the invention is generally composed of two components of air duct of generally curvilinear or rounded cross section arranged with their axes generally in the same plane and intersecting at an angle at the plane of intersection. The first of said ducts, which is connected to the air circuit at a plane of intersection at the upstream end of the classifier, is of expanding cross section so that the plane of intersection of the ducts has a cross sectional area which is at least about 1.5 times, and preferably between about 1.5 and 3 times, the area of the plane of connection of the first component at the upstream end of the classifier with the air circuit. The angle of intersection of the two components of duct is a critical factor in achieving accurate classification in the apparatus of the invention. In the first place, the upstream component of duct in the classifier must be arranged so that the bottom of it makes an angle of at least about 38° with the horizontal in order that material separated from the air stream will flow back down it under the influence of gravity. In the second place, entrained particles within the size range which it is desired to remove from the air stream in the said first component of duct when carried along past the plane of intersection of the two components should strike the outer wall of the second component at a sufficient angle at least momentarily to stop movement thereof in the direction of the axis of the second of said duct components so that, with the air stream at that point having a velocity which will not be sufficient to carry them on upwardly out of the classifier, they will be permitted to flow back down along the lower surface of said first component of duct from where they may be removed through a suitable opening covered by a foraminous member having a collector beneath it.

In order for the above mentioned separating action to take place, it has been found that the angle between the axes of the two components should not be more than about 128° and the axis of the first component when extended should intersect the outer wall of the second component to form an acute angle with the tangent plane at the point of intersection of not less than about 38° . On the other hand, if the particles, once stopped by impingement upon the outer wall of the second component, are not once again to be picked up by the air stream and carried out of the classifier the velocity of the air stream at that point must be materially less than the velocity of the air stream at the plane of intersection of the classifier and the air circuit. Accordingly the cross sectional area of the second component of duct at that point must be greater than the cross sectional area of said plane of connection. In order to eliminate the possibility of the air stream having sufficient velocity to re-entrain the particles which it is desired to separate in the classifier the angle between the axes of said two components should not be less than about 94° . In practice it has been found that an angle of intersection of the axes of the ducts which is between about 115 and 125° is satisfactory for most purposes, although the optimum angle will depend to some extent upon the nature of the material being reduced and the nature and size of the particles which it is desired to recover from the air stream in the classifier.

Since the whole action of the classifier according to the invention is based upon the effect produced in the region of the intersection of the two components of duct, it is important that the first component of duct should be sufficiently long for the air stream as it approaches the plane of connection to have reached a substantial equilibrium of flow, and in this connection it has been found that the length of the axis of the first component between the plane of connection and the plane of intersection should be at least 2.4 times the mean diameter of the plane of connection.

Similarly, it is important that the second component of duct be sufficiently long to embrace the whole zone of separation of particles from the air stream, and in this connection it has been found desirable to have the second component at least 1.5 times as long as the mean diameter of the plane of intersection.

The invention will be more fully understood by reference to the following detailed specification taken in conjunction with the accompanying drawings which illustrate a number of embodiments thereof.

In the drawings:

Figure 1 is a general view of a material reduction mill equipped with a classifier according to the invention illustrating the general arrangement of the classifier in relation to the other components of the mill;

Figure 2 is a detailed side view of a classifier according to the invention partly broken away to illustrate details thereof;

Figure 3 is a fragmentary view of the classifier shown in Figure 2, with the products collector removed to illustrate the mounting of the foraminous member and vibrator;

Figure 4 is a detailed view of another classifier according to the invention, partly cut away to illustrate detail; and

Figure 5 is a general side view of an apparatus according to the invention illustrating the manner in which a number of classifiers according to the invention may be mounted in series for purposes of collecting a series of different sized products having predetermined size-weight characteristics.

Referring now more particularly to the drawings, the general arrangement of the components of the material reduction mill in connection with which classifiers according to the present invention may be used to advantage is illustrated in Figure 1.

The mill comprises the cylindrical drum 10 mounted for rotation on hollow trunnions housed in the bearings 11 and 12. The gear 13 is mounted on the drum 10 and is driven by drive pinion (not shown) to rotate the drum at the required speed. Material is fed to the drum, for instance, from the conveyor 14 and falls into the feed chute 15 and into the drum through the hollow trunnion which is mounted in the bearing 11.

Comminuted material is withdrawn from the drum 10 in an air stream which is drawn through the feed chute 15 and across the mill to entrain and remove particles below a certain size-weight factor. The air stream is passed through an air circuit, which on the downstream side of the mill, contains a number of components for separating products and delivering them for disposal. The classifier of the present invention consists of two sections of duct and is indicated generally on Figure 1 by the numeral 16. It consists essentially of the duct component 17, the duct component 18 and the coarse products collector 19. The duct components 17 and 18 may be constructed in conventional manner and preferably are rubber lined.

Above the classifier 16 there may be mounted a by-pass gate 25 which consists simply of a gate establishing communication between the interior of the air circuit and the atmosphere by means of which it is possible, by adjusting the degree of opening thereof, to adjust the speed of the air stream passing through the drum and through the classifier. The air stream is delivered to the main products collector 20 and then passes through duct 21 to the impeller 22 driven by motor 23 and is exhausted to atmosphere through the dust collector 24.

The mill thus described is an open circuit one, but it will be appreciated that the invention can be used equally as well in mills employing a closed air circuit.

Turning now to Figures 2, 3 and 4, it will be observed that the classifier 16 comprises duct components 17 and

18 which are mounted in particular relationship one to another and are of particular shapes and sizes.

The upstream duct component 18 is of generally rounded or curvilinear cross section and is adapted, at its upstream end 26, to fit into the hollow trunnion on the outlet side of the mill forming a plane of connection 26a therewith. As shown in Figures 2 and 3, the duct component 18 is made in two sections joined at 27. This, however, is merely for convenience of manufacture and is unimportant insofar as the present invention is concerned. The duct component 18 is of generally expanding cross sectional area and terminates in a flange 28 which is adapted to connect to the flange 29 on the duct component 17 so that a plane of intersection 30 is formed between the two duct components 17 and 18.

The downstream duct component 17 is also of curvilinear or rounded cross section and may either be of uniformly cross sectional area, of expanding cross sectional area or of diminishing cross sectional area, depending upon what other components besides the classifier 16 are to be in the air circuit on the downstream side of the drum 10.

The upstream duct component is provided on its lower side with the opening 31 which is covered by the foraminous member 32 which is illustrated as being a screen and which may be a screen having a pre-determined mesh size in the event that oversize is to be returned to the drum 10, or may be formed from a punched metal sheet in the event that all material withdrawn from the airstream by the classifier is to be collected. Secured in position below the foraminous member 32 is the hopper 34 which delivers coarse products collected therein through the rotary air lock 35 which is of conventional design and is arranged to deliver products through the delivery chute 36 without permitting air to be drawn into the hopper 34. This is accomplished, for instance, by a rotary airlock having a number of rotating vanes 37. In the event that a screen of pre-determined mesh size is used to cover the opening 31, normally speaking there will be a vibrator 38 mounted more or less centrally upon the screen 32.

The dimensions of the duct component 18 and the angle at which the duct components 18 and 17 intersect each other is of critical importance to the invention. In the first place the duct component 18 must be arranged to lie with its lower side at an angle of at least 38° to the vertical in order to assure the free flow of material withdrawn from the airstream within it, back towards the drum 10. Secondly, the area of the plane of intersection 30 must be at least 1.5 times the area of the plane of connection 26a. Thirdly, the length of the axis of the duct component 18, between the plane of connection 26a and the plane of intersection 30, must be at least 2.4 times the mean diameter of the plane of connection 26a. Fourthly, the duct components 17 and 18 must both be of a generally rounded or curvilinear cross section. In this respect they may be round, oval, etc. but should not be rectangular for maximum efficiency. Fifthly, the angle of intersection between the central axes of the duct components 17 and 18 must be between about 94° and 128°. Sixthly, the central axis of the duct component 18, when extended, must intersect the outer wall of the duct component 17 to form an angle β with the tangent plane at the point of intersection which is not less than about 38°. Finally, the duct component 17 must be at least 1.5 times as long as the mean diameter of the plane of intersection 30.

The above listed critical features in the design of the classifier of the invention are largely empirical, although when the theory of the separation of particles in the classifier according to size-weight factor is considered, the reasons for the various critical features involved become apparent. In theory the classifier of the invention is believed to operate as follows:

The airstream passing through the drum 10 will entrain all particles within the mill whose paths of travel intersect it, and the size-weight factors whereof are below a given value. If the material being comminuted is of uniform specific gravity, density and physical form, the particles removed from the mill will all be below a given size; however, many rocks and ores consist of agglomerates of two or more different materials having different specific gravities, different physical forms and/or different densities in their primary crystalline state, for instance, in the case of asbestos ore, the primary

crystals have a specific gravity which is not very much different from the specific gravity of the host rock, but the primary crystals occur as long fibres having a relatively large surface area compared, for instance, to a sphere, and are thus much more easily picked up by an airstream than a theoretically round piece of material of the same size would be. Thus, with most materials the particles picked up by the airstream passing across the drum of the mill will be either picked up by the airstream or rejected by it, depending upon a factor which is a function of the size of the particle, the weight of the particle and the physical state thereof. For convenience of reference herein, I will refer to this factor as being the "size-weight factor" of the material. With respect to any given material this factor is the one which determines whether a given particle will be picked up and carried along by a stream of air of given velocity or whether it will not be picked up and carried along by the said stream of air.

The particles picked up by the airstream crossing the drum 10 are carried along past the plane of connection 26a where they enter the duct 18. In order to move along the duct 18, particles must change direction so that the heavier of them will strike the lower surface of the duct and lose some of their momentum. However, since the airstream within the lower portion of the duct 18 has a higher velocity than the airstream at the point of the plane of intersection due to the lower cross sectional area of the duct, particles will be re-entrained unless they are of such a large size-weight factor that their presence within the lower portion of the duct 18 may be considered as having been brought about by causal circumstances. The entrained particles proceed up the duct 18 until they approach the plane of intersection 30 at which point the airstream undergoes a change in direction and the coarse particles (we are here concerned mainly with the coarse fraction of the products of the mill) will have considerable momentum because of the fact that the velocity of the airstream in duct 18 will normally be of the order of five to six thousand feet per minute. All the particles, therefore, except the very fine products, will tend to continue straight on and will strike the outer wall of the duct component 17. The duct 17 is placed at such an angle to the duct 18 that particles striking the outer wall thereof will lose substantially all of their motion in the direction of the axis of the duct 17. Normally, however, they will rebound off the wall back into the airstream at which point they will either be re-entrained by the airstream flowing in the duct 17 or they will fall back and slide by gravity down the bottom side of the duct 18 from where they may be removed through the foraminous member 32. It might be mentioned at this point that, even if all of the material thus removed from the airstream is to be collected by the coarse products collector 19, it is essential to have either a screen or a punched plate over the opening 31 to preserve the flow characteristics of the duct 18; otherwise, the products collected will become seriously contaminated with fines.

Whether or not a particle placed substantially motionless in an airstream will be entrained or will settle out from the stream depends upon the aforementioned size-weight factor, and by controlling the velocity of the airstream within the duct 17 the size-weight factor of the particles withdrawn from the stream and returned to duct 18 can be controlled within a surprising degree of accuracy. Furthermore, the coarse particles withdrawn and returned will be substantially free of fines and dust.

Turning to the critical features above mentioned and relating them to the above expressed theory of operation of the classifier, it will be apparent that since the airstream passing through drum 10 has picked up particles from a substantial stand still in the drum, the diameter of the duct 17 in the area of the plane of intersection 30 will have to be somewhat greater than the area of the stream as it leaves the drum; otherwise all the particles knocked out of the airstream by impinging upon the surface of the duct 17 will be re-entrained. It has been found in fact, that to get efficient separation, the area of the plane of intersection should be at least 1.5 times the area of the plane of connection 26a. Since the separating action at the intersection of the two duct components depends primarily upon each particle having gained enough momentum in the general direction of the axis of the duct 18 to impinge upon the outer surface of

the duct 17, the duct 18 must be sufficiently long to enable flow conditions to return substantially to normal after the change of direction brought about at the plane of connection 26a. Experimentally it has been found that the length of the duct 18 should be at least 2.4 times the mean diameter of the plane of connection 26a.

The duct component 17 must be long enough to provide a substantial length of duct in which the separating action can take place, and in general its length should not be less than 1.5 times the mean diameter of the plane of connection 30. The outer wall of the duct 17 must form a sufficient angle with the extended axis of the duct 18 to ensure that particles striking it will lose substantially all their velocity in the direction of the axis of the duct 17. It has been found in practice that an angle greater than about 38° will ensure an efficient separating action in this respect. Similarly the axes of the ducts 17 and 18 should meet at an angle which is between about 94° and 128° to ensure a sufficient change in direction of the airstream.

The duct sections 17 and 18 should be curvilinear or rounded in cross section because, if they were rectangular with sharp corners, various secondary flow conditions would arise, interfering with the accurate separation action of the classifier, and tending to deposit fines and so forth, as well as the products which it is desired to withdraw. If, however, a substantial quantity of fines can be tolerated in the coarse product to be collected, the duct can be made with a square or rectilinear cross section.

The classifier according to the invention may, if desired, be arranged in series with a number of other such classifiers, as illustrated by Figure 5 which shows three classifiers according to the invention, arranged in series to collect three products of gradually decreasing size in the hoppers 40, 41 and 42. In this case it will be observed that component 43 is the first component, and component 44 is the second component with respect to component 43 but is the first component with respect to component 45, while component 45 is likewise the second component with respect to component 44 but the first component with respect to component 46. The type of arrangement illustrated in Figure 5 may be used to advantage in cases where differential grinding may be used to benefit the material undergoing comminution, to simplify subsequent purification steps, or, for instance, in the making of abrasive products where it is desired to get products in different size ranges from a material undergoing reduction which is of a uniform composition and density. In the latter case the arrangement illustrated in Figure 5 may be used to produce a number of products, each one of which will have an accurately regulated particle size and will be substantially free from dust.

From the foregoing it will be appreciated that the present invention produces a simple effective classifier for carrying out the objects aforesaid. The foregoing description, however, is not to be construed in any limited sense, the invention and its scope being defined in the appended claims.

What I claim as my invention is:

1. A classifier for removing and recovering from an airstream entrained solid particles having a size-weight factor above a predetermined value, said classifier comprising (a) two components of duct arranged with their longitudinal axes in substantially the same plane and intersecting at an angle, said components meeting along a plane of intersection; said classifier being adapted to form part of an air circuit, and receive an air stream at a plane of connection thereof with a component of said air circuit upstream of said classifier; the area of said plane of intersection of said ducts being at least about 1.5 times the area of said plane of connection; the angle between the longitudinal axes of said two components being between 128° and 94°; the longitudinal axis of said first component, when extended, intersecting the outer wall of said second component to form an acute angle with the tangent plane at the point of intersection of not less than about 38°; the length of the longitudinal axis of said first component between said plane of connection and said plane of intersection being at least 2.4 times the mean diameter of said plane of connection; said second component being at least 1.5 times as long as the mean diameter of said plane of intersection; said first component having a lower side downwardly inclined towards the

upstream end thereof to provide for downward flow thereover of deposited material, said lower side having an opening formed therein; (b) a foraminous member generally corresponding in size and shape with said opening and secured in position to cover said opening, and (c) means arranged beneath said foraminous member for collecting particles which pass through said foraminous member.

2. A classifier as defined in claim 1 in which the angle between the axes of said two components of duct is substantially 125° and the axis of said second component of duct is substantially vertical.

3. A classifier as defined in claim 1, in which said two components of duct are generally curvilinear in cross section throughout their length.

4. A classifier as defined in claim 3, in which the angle between the axes of said two components of duct is substantially 125° and the axis of said second component of duct is substantially vertical.

5. A classifier as defined in claim 4, in which said second component of duct is of gradually diminishing cross section.

6. A classifier as defined in claim 1, in which said foraminous member is a punched sheet having foraminations therein large enough to allow the largest of the particles removed from the airstream in the classifier to pass therethrough.

7. A classifier as defined in claim 1, in which said foraminous member is a screen of predetermined mesh size, and comprising vibrator means mounted on said screen to facilitate passage of comminuted material through said screen into said means for collecting particles which pass through said foraminous member.

8. A classifier as defined in claim 1, in which said means for collecting particles which pass through said foraminous member include a hopper secured to said first component of duct, a delivery chute at the base of said hopper, and means within said delivery chute for preventing passage of air upwardly into said hopper.

9. A classifier as defined in claim 8, in which said means for preventing passage of air upwardly into said hopper comprises a rotary air lock.

10. A classifier as defined in claim 1, in which the area of said plane of intersection is between about 1.5 and about 3 times the area of said plane of connection.

11. A classifier comprising a plurality of components

of duct, including a first component and a last component, said components being arranged in series with their longitudinal axes intersecting at angles, each component of duct meeting the subsequent one at a plane of intersection; 5 said first component being adapted for connection to a component of an air circuit, forming a plane of connection with said component; the area of the plane of intersection of said first component with the subsequent one being between about 1.5 and 3 times the area of said plane of connection, each succeeding plane of intersection being between about 1.5 and 3 times the preceding one; the axes of connected components of duct intersecting at an angle of between 94° and 128° ; the axis of said first component of duct being at least about 2.4 times the mean diameter of said plane of connection; the axis of each succeeding component of duct except said last component being at least 2.4 times the mean diameter of its plane of connection with the preceding component of duct; the axis of said last component of duct being at least about 1.5 times the mean diameter of the plane of connection thereof with the preceding component of duct; said first component of duct leading upwardly at about 38° to the horizontal, each succeeding component of duct extending generally upwardly; openings on the lower sides of each of said components of duct except said last component; foraminous members covering said openings; and means disposed beneath said foraminous members for collecting material passing therethrough.

12. A classifier as defined in claim 11, in which said components are all of generally curvilinear cross section.

13. A classifier as defined in claim 11, in which said foraminous members are screens of predetermined mesh size, each succeeding screen being of smaller mesh size than the immediately preceding one.

14. A classifier as defined in claim 13, including vibrator means mounted on each of said screens.
